AMUSEMENT APPARATUS

Hyla F. Maynes, Menands, N. Y., assignor of
one-half to Emma C. Maynes

Application July 21, 1944, Serial No. 545,945

9 Claims. (Cl. 115—0.5)

This invention relates to aquatic amusement apparatus and particularly to novel passenger-carrying boat means.

The present invention affords improved boat means for use in conjunction with amusement apparatus similar to that disclosed in my prior Patent No. 2,343,313, granted March 7, 1944. The boat of the present invention, like that of my prior patent, is suspended and supported by an encircling, relatively large, pneumatic tire. However according to the present invention, the boat proper is rotatable within the supporting tire, whereby it may be freely and quickly turned without the considerable added friction incident to turning the supporting tire. This makes the boat of the present invention more readily maneuverable than has heretofore been the case.

Further, according to the present invention, the boat proper may be freely steered to and propelled in any desired direction regardless of the condition of rest or rotation of the supporting tire. Anti-friction means are preferably but not necessarily provided to further render the boat itself rotatably independent of the supporting tire.

The boat of the present invention is provided with fluid pressure motor means for propulsion thereof and has suitable fluid pressure storage means. As a practical matter boats of the type here in contemplation are usually used at carnivals, fairs and other places of public amusement and individual rides are of relatively short duration. It is accordingly highly practical to provide an air pressure reservoir or tank and the shape of the tank herein disclosed is such as to safely carry desired air pressures without extraordinary structural reinforcement, while still working conveniently into the design of the boat and not requiring the latter to be unduly enlarged by reason of the tank.

Other objects and advantages of the present invention will occur to those skilled in the art from a consideration of the accompanying drawings and the following detailed description of an exemplary embodiment of the principles of the invention.

In the drawings:

Fig. 1 is a longitudinal vertical cross-sectional view of the form of boat shown herein by way of example; and

Fig. 2 is a fragmentary top plan view thereof with the hull in cross section.

In the drawings like characters of reference denote like parts and the numeral 10 designates a generally annular side wall portion of sheet

metal, the bottom wall of the boat hull comprising a plate designated 11. The annular side wall 10 extends inwardly at its bottom edge to provide an annular flange 12 and thence extends upwardly to provide an upstanding inner wall portion 13. The top of the annular space thus formed is closed off by an annular plate 14 having upstanding inner and outer flanges 15 and 16 to facilitate hermetic sealing of the annular tank space 17. The assembled tank is designated generally 18.

For propulsion purposes the bottom plate 11 is provided with a downwardly extending motor casing 20 which houses an air operated motor 21 which may be of any convenient and commercially available form. The output shaft of motor 21 is designated 22 and extends rearwardly through a suitable bearing formed in casing 20 to carry a propeller 24. A conduit 25 extends between the interior of the annular tank space 17 and the motor 21 and is provided with a throttle valve (not shown) which is controlled from a foot operated accelerator pedal 28.

The pedal 28 has a pivot bearing support 29 and a downwardly extending arm 30 which extends through a clearance opening in bottom plate 11 and pivotally engages a link 31. The other end of link 31 pivotally engages a throttle arm 32 and the entire throttle assembly is normally biased to a throttle-closed position by an extension spring 34 which engages between arm 30 and a lug 35 fixed to the bottom of plate 11. Depression of accelerator pedal 28 opens the throttle valve to any desired degree.

Between runs the pressure in tank 18 may be replenished through a conduit 38 which terminates in a conventional normally closed fitting 39. The manner in which a pressure supply conduit is fixed to the fitting 39 for replenishing tank pressure is known to those skilled in the art and need not be further described.

Resting upon the upper surface of the storage tank is a seat base 50 and a seat cushion 51. The forward portion of the seat base 50 and cushion 51 is designated 52 and is readily removable to give access to the lower central compartment. A step 53 is disposed forwardly of the seat cushions 51, 52 and is narrow enough transversely to be straddled by an occupant. The step 53 is used in entering and leaving the boat. The back and sides of the annular wall 10 are cushioned as at 54 to complete the upholstery of seat.

The direction of the boat is controlled by means of a rudder 60 and the manner in which such control is effected will now be described. A

bracket 61 extends inwardly from the forward wall 10 and rotatably supports a steering wheel 62. A steering arm 63 fixed for rotation with wheel 62 has a downwardly extending link 64 for engagement with an end of a rocker arm 65 having a fixed pivot axis. The other end of rocker arm 65 engages a link 66, and a rudder supporting shaft 67 extends upwardly through bottom plate 11 to carry a laterally extending arm 68 which likewise engages link 66. It is believed the operation of the steering linkage is obvious from the foregoing.

It will be noted that the shape of the boat hull, the shape of the storage tank and the disposition of the seating and entering devices and the control elements are such that the presence of the storage tank does not materially add to the required size of the boat. In the main, space that would otherwise be unavoidable waste space is utilized, and at the same time such space permits the employment of a truly annular tank with its obvious advantages from the standpoint of structural resistance to relatively high internal pressures.

An annular angle iron 75 encircles the annular wall 10 of the boat and provides a raceway for a series of anti-friction balls 76. A pneumatic tire casing is designated 80 and such casing may be mounted upon a conventional drop center rim 81. The upper flange of rim 81 comprises an opposed raceway for the anti-friction balls 76 so that the entire boat is freely rotatable within its supporting pneumatic tire casing 80 and the foregoing structure provides anti-friction bearing against both radial and annular thrust.

The casing 80 is provided with the usual inner tube 84 and in Fig. 1 a suitable tire valve is designated 85. With the structure thus far described the entire boat including its propulsion and steering mechanisms may merely be hoisted from its position of assembly within the tire 80. To prevent accidental dislodgement of the boat hull the bottom plate 11 has pivoted thereto a series of fingers 90 which in the position illustrated in Fig. 1 prevent lifting of the boat relative to the tire by engagement against the lower flange of rim 81 if such lifting be attempted. Ample clearance between the rim flange and fingers 90 is preferably provided, to avoid friction, since the hull will normally be supported entirely by the ball bearing upper annular support. When it is desired to disassemble the boat and its supporting tire the fingers 90 are merely pivoted aside.

While a complete and specific embodiment of the plans of the present invention have been described in detail by way of example, it is to be understood that the spirit and scope of the present invention are not limited otherwise than as defined in the appended claims.

I claim:

1. In amusement apparatus, a boat hull having a substantially cylindrical side wall, and a pneumatic tire extending around said side wall for buoyantly supporting the hull and comprising a resilient bumper, said hull and said tire being freely rotatable relative to each other.

2. In amusement apparatus, a boat hull having a substantially cylindrical side wall, and a pneumatic tire extending around said side wall for buoyantly supporting the hull and comprising a resilient bumper, said hull and said tire being freely rotatable relative to each other, and propulsion means and steering means carried entirely by said hull at the lower portion thereof and projecting beneath the lower side of said tire.

3. In amusement apparatus, a boat hull and a pneumatic tire extending around said hull for buoyantly supporting the hull, said hull and said tire being freely rotatable relative to each other, and propulsion means carried by said hull at the lower portion thereof and projecting beneath the lower side of said tire.

4. In amusement apparatus, a boat hull and a pneumatic tire extending around said hull for buoyantly supporting the hull, said hull and said tire being freely rotatable relative to each other, and propulsion means, and steering means carried by said hull at the lower portion thereof and projecting beneath the lower side of said tire.

5. In amusement apparatus, a boat hull having a substantially cylindrical side wall, a pneumatic tire extending around said side wall for buoyantly supporting the hull and comprising a resilient bumper, and anti-friction bearing means between said hull and said tire whereby they are freely rotatable relative to each other.

6. In amusement apparatus, a boat comprising a substantially cylindrical body portion, a pneumatic tire surrounding said body for buoyantly supporting the same, and means associating said body portion and said tire for free relative rotation.

7. In amusement apparatus, a boat comprising a substantially cylindrical body portion, a pneumatic tire surrounding said body for buoyantly supporting the same, and anti-friction bearing means associating said body portion and said tire for free relative rotation.

8. In amusement apparatus, a boat comprising a substantially cylindrical body portion, a pneumatic tire surrounding said body for buoyantly supporting the same, means associating said body portion and said tire for free relative rotation, and propulsion and steering means carried entirely by said body portion at the lower portion thereof and projecting beneath the lower side of said tire.

9. In a boat, a hull having a substantially cylindrical side wall and a bottom wall, means defining an annular fluid pressure reservoir within said side wall and extending about the lower portion thereof, a passenger seat above a portion of said reservoir whereby a seated passenger employs the central open space defined by said reservoir for leg room, a casing portion extending below said bottom wall, a fluid pressure actuated propulsion motor in said casing portion and connectible with said reservoir for operating the boat, and a pneumatic tire extending around said side wall for buoyantly supporting the hull, said hull and said tire being freely rotatable relative to each other.

HYLA F. MAYNES
